[57] CLAIM

The ornamental design for a convertible computer workstation, as shown and described.

DESCRIPTION

FIG. 1 is a front perspective view of a convertible computer workstation, showing my new design with a computer housing cover in open condition a computer and related components being shown in broken lines for illustrative purposes only;

FIG. 2 is a front perspective view thereof with the computer housing cover closed;

FIG. 3 is a top plan view thereof;

FIG. 4 is a front elevational view thereof with a computer being shown in broken lines for illustrative purposes only;

FIG. 5 is a rear elevational view thereof;

FIG. 6 is a bottom plan view thereof;

FIG. 7 is a right-side elevational view, the left side being a mirror image thereof;

FIG. 8 is a rear perspective view thereof;

FIG. 9 is a vertical sectional view taken along lines 9—9 of FIG. 4 of the right half thereof; and,

FIG. 10 is a vertical sectional view taken along lines 10—10 of FIG. 4 of the left half thereof.
